UNITED STATES PATENT OFFICE

FRANCIS V. BIRBECK, OF AROMAS, CALIFORNIA

CRATE

Application filed January 21, 1930. Serial No. 422,336.

This invention relates particularly to a crate for packing lettuce or similar produce.

It is one object of the invention to provide a crate that will permit free ventilation at all 5 times, and yet will be rigid in construction, light, strong, and durable.

It is another object of the invention to provide a crate of the character indicated that will be economical to manufacture, quickly 10 and easily assembled, of few parts, and highly efficient in its practical application.

In the drawing:

Figure 1 is a perspective illustration of a crate embodying my invention.

15 Figure 2 is an end view of the crate shown in Figure 1 with the side, bottom, and end sections separated.

In my improved crate the two side sections are identical in form and construction and 20 therefore a detailed description of one applies equally as well to the other, and the same is true of the two end sections.

Referring now more particularly to the drawing, the bottom section comprises the 25 two end bars 1 and 2, somewhat shorter than the finished width of the crate, and upon these are nailed the bottom slats 3 in spaced relation to each other as shown. On the ends of the slats 3 are nailed cleats as 4 and 5 in 30 parallel relation with the bars 1 and 2 and aligning with the ends of the slats 3. This bottom section is complete in itself and forms one unit of the crate.

Each side section comprises two end bars 35 6 and 7 equal in length to the height of the finished crate less the thickness of the bottom slats 3 and cleats 4-5. These bars are rabbed at both ends and on the same or inner side as at 8 and 9, and on the sides opposite 40 to the rabbets are mounted spaced slats 10, the slats 10 being equal in length to slats 3 and determining the length of the crate. On the ends of the slats 10 are nailed cleats 11 and 12 in parallel relation to bars 6 and 7 and 45 aligning with the ends of slats 10.

Each end section comprises a top bar 13 equal in length to bars 1 and 2 and having slats as 14-15-16 mounted on one side thereof in spaced relation to each other and 50 at right angles to the said bar, the two end

slats 14 and 16 extending a distance beyond the ends of the bar as shown.

It will be noted that in this construction but three distinct units are required, and these units are so constructed that they may be made up cheaply and in large quantities by machine and assembled as hereinafter set forth.

In assembling the crate it is only necessary to place the side sections in position with the rabbets 8 engaging the ends of the bottom bars 1 and 2 and secure by suitable nailing. The end sections may then be dropped into position with the top bars 13 seated in rabbets 9 and the slats 14-15-16 overlapping the end bars of the side sections and the end bars of the bottom section to which they are securely nailed.

By means of this construction the several 60 sections may be machine made and the assembling may be effected by unskilled labor thereby considerably reducing the cost of the finished product and at the same time insuring proper spacing of the slats.

Another advantage of this construction is that the cleats 4-5, 11-12 not only complete their respective sections and render 65 them rigid and strong but they also serve to space the adjoining crates when loaded in a car, thereby permitting free ventilation on all sides.

Still another advantage of this construction is that the end sections may be simply made and of few parts, and yet they serve 85 to effectually tie the bottom and side sections together into one rigid whole.

It is to be understood, of course, that while I herein show and describe but one specific embodiment of the invention, changes in form, construction, and method of assembly 90 may be made within the scope of the appended claims.

I claim:

1. A crate comprising, a bottom section including a plurality of slats having end bars mounted thereon and end cleats mounted thereon opposite the bars, two side sections, each section including a plurality of slats having end bars mounted thereon and end cleats mounted thereon opposite the bars, 95 100

- the end bars of the side sections being mounted upon and secured to the ends of the end bars of the bottom section, and a pair of end sections including top bars mounted upon
- 5 the upper ends of the end bars of the side sections and slats overlapping and secured to the end bars of the bottom and side section.
2. A crate comprising, a bottom section
- 10 including a plurality of slats having end bars mounted thereon, two side sections, each section including a plurality of slats having end bars mounted thereon, each end bar having a rabbet formed on one end to seat
- 15 upon one end of one of the bottom end bars whereby to lie in the same plane therewith with the slats disposed outwardly of the crate, and a pair of end sections, each end section comprising a top bar having a plurality
- 20 of slats mounted thereon adapted to overlie the inner sides of the adjacent end bar of the bottom section and end bars of the side sections, the upper ends of the end bars of the side sections having rabbets
- 25 formed therein to receive the ends of the top bars.

FRANCIS V. BIRBECK.
